UNITED STATES PATENT OFFICE

FERMIN ROCAMORA, OF SABADELL, SPAIN

MACHINE FOR CLEANING, IMPROVING, AND SOFTENING WOOL AND OTHER TEXTILE MATERIALS

Application filed February 1, 1929, Serial No. 336,762, and in Spain November 20, 1928.

My invention consists of a machine for improving, softening and cleaning wool or other textile materials on leaving the card or the combing machine, either in the form of a 5 lap or sheet of fibres or in the form of a ribbon, or sliver. This machine, applied to the wools, to which it is specially destined, separates by beating and shaking combined, the so-called dog hair or dead-hair, as well as 10 the short and thick fibres, straws and other solid impurities, which in variable proportion, according to classes, are contained by the wools, even after being submitted to the usual processes of cleaning and preparation. 15 Spanish wools, especially the middling fine qualities, contain an important quantity of dog hair which considerably depreciates the industrial value of this textile matter, chiefly due to the impossibility of being able to dye 20 by any means as yet known, the defective fibres. Besides which, from whatever origin they may be, wools always contain a certain proportion of thick and short fibres, likewise defective, whose length varies between one 25 and three centimetres, which it has also not been able to eliminate until now, in sufficient proportion, even by means of the most improved combers, which are the only machines with which it is possible to separate these 30 fibres, although in an insignificant quantity.

The presence of short and thick fibres in the rovings obtained with the preparation machines renders difficult the thick or fine spinning of the wool, because when passing 35 through the organs of the spinning machines they occasion frequent breaking of the thread, which represents an important shrinkage in production and a considerable waste of raw material. On the other hand, 40 these short-lengthened fibres possess a rigidity which is observable in the textures, specially in cloths, in which the said fibres, cut by the cloth-shearing machine, give them a certain roughness to the touch, which is 45 detrimental to the quality of the fabric.

The object pursued by the invention of my machine is to be able to separate from the laps or slivers of wool, almost completely and with an acceptable yield, both the dog 50 hair and the short thick fibres, and at the

same time finishing the cleaning of the fibres of all the solid impurities and obtaining a greater flexibility in the remaining fibres, which will have a softness or feel hitherto unknown in this line. 55

The machine of my invention essentially comprises a succession of horizontal rulers longitudinally grooved, supported by arms having a rapid oscillatory motion, and intercalated between couples of rollers which carry 60 the fibres submitted to treatment.

The fibres, when combed or carded and disposed either in the form of lap or of sliver which are developed from a usual creel, or from an adequate support, pass by a guide of 65 the machine which juxtaposes them in order to form one or more laps, and in this form the fibres are carried by the guiding rollers of the machine, passing alternately through the grooves of the oscillating rulers, which, with 70 their rapid motion, beat on both sides and intensively shake the lap of fibres separating by inertia, due to their greater density, the defective fibres and solid impurities which were not eliminated by the combing or card- 75 ing.

On leaving the last couples of the guide-rollers situated at the end of the machine, the laps of fibres are stretched and combed, forming one or more rovings which are finally 80 wound in the shape of crossed bobbins. For these complementary operations, there is placed next to the outlet end of the cleaning machine a "Gill intersecting" or other similar mechanism. 85

The oscillating arms which support the grooved rulers of the machine may be simply, with one single ruler, or better still, double, in the shape of a balance-beam, having, in this case, two rulers, one at each end. 90

In the accompanying drawings is shown a form of execution of the machine of this invention.

Figures 1 and 2 show an elevation and partially a plan view, respectively, of the cleaning machine, mounted with its corresponding feeding apparatus and auxiliary engine for the final complementary processes. 95

In Figs. 3 and 4 is shown, on a larger scale, in elevation and plan view, respectively, a 100

part of the machine which comprises the just unit or group of shaker rulers and guide rollers corresponding to the entry of the machine.

5 Fig. 5 shows on a still larger scale, the mechanism which actions the shaker rulers, seen in vertical section through line V—V of Figure 6.

10 Fig. 6 is a vertical section of this mechanism, through line VI—VI of Figure 5.

15 Fig. 7 is a vertical section through line VII—VII of Figure 6, and finally Figure 8, a variation of this same, in which the shaker comprises a single ruler mounted on simple arms.

20 The machine shown comprises, as an example, a framework 1 which carries, suitably distributed, a series of framework supports 2 which support the shaking mechanisms. 25 Mounted upon bearings 3 leaning alternately on the upper part of the frames 2 and on the bases of the foundation 1 of the framework, the machine comprises several pairs of guide rollers 4 which turn at the same speed, driven simultaneously by means of a transmission chain 5 coupled to wheels 6 fixed on to the axles of the lower rollers which act as motors to each couple and to another wheel 7 fixed to a driving shaft 8 transverse to the machine.

30 Each of the supports 2 supports, upon the sides thereof by means of bearings 10, 18, two transverse axles 9. These axles 9 driven by means of a mechanism described later, have a rapid oscillatory motion which is transmitted to two horizontal rulers 11 slotted longitudinally, fixed on to the ends of arms 12 mounted on the said axles 9. By providing the slots and passing the fibre therethrough, the fibre rulers will be so related that when 40 movement is imparted to the rulers, the fibre will be effectually shaken.

45 These axles 9 are oscillated by a driving shaft 16 laterally mounted lengthwise to the machine and provided with pulleys 17. These pulleys 17 are coupled by means of semi-crossed straps or belts with the pulleys 15 each of said pulleys being fixed to a crank shaft 14 (Figs. 5 and 6) which gyrates between the branches of a fork 13 fixed to the 50 end of each axle 9, the crank shafts 14 bearing on the same bearing supports 10 which support the said axles 9.

55 The oscillating arms 12 which support the rulers, may be arranged singly (Fig. 8) each axle 9 moving a single ruler or double (Fig. 7) arranged like a balance-beam with a ruler at each end.

60 At the end corresponding to the entry of the machine and supported by means of supports 19 fixed to the frame of the same, a guide is placed formed by a horizontal ruler 20 placed transversely with a series of holes close to one another. This guide serves to juxtapose in an orderly way the slivers, 65 passing them through the said holes at the

outlet of the creel in order that they may reach the first couple of conducting rollers 4 of the machine in the shape of one or more laps.

65 The entire installation set as an example of the cleaning machine which is the object of the invention, with its auxiliary feeding apparatus and complementary stretching machine (Figs. 1 and 2) comprises a creel 21 of the already known type, provided with 70 four superimposed rows of pairs of rollers which develop by friction the slivers of the bobbins 22 arranged in horizontal series and leaning on the said pairs of rollers, with a tangential speed equal to that of the guiding 75 rollers 4 of the machine. The slivers suitably arranged by the exit guide of the creel, pass through guide 20 which juxtaposes them, forming the laps and enter into the machine already described, composed of three groups 80 of three units each group. Between the intermediate group and the first and third groups, and fixed on to the framework of the machine, there are intercalated two pairs of guides 23 of a helicoidal shape, which invert the faces 85 of the laps 24 of fibres.

90 At the end of the cleaning machine is placed an auxiliary machine 25 of the already known type "Gill intersecting" which takes the laps of fibres at their exit from the last pair of guiding rollers 4 of the cleaning machine, giving them a complementary stretching and 95 combing, reuniting them afterwards and forming a sliver or roving which is wound in a crossed bobbin.

100 The cleaning machine can also be fed with laps or sheets of fibres instead of bobbined slivers, in which case the creel is substituted by a suitable support to develop the rolls of lap, and the perforated guide ruler 20 placed 105 at the entry of the machine, is substituted by another which has two grooves like those of the oscillating shaking rulers.

I claim:

110 1. A machine to soften carded and combed textile fibres and to separate from them the defective fibres and impurities, having in combination a series of rulers to impart shaking movement to the fibres, said rulers being supported by arms, means for rapidly oscillating said arms, and a series of guiding and feeding rollers for presenting said fibres to the action of the rulers which beat and shake them repeatedly.

115 2. A machine to soften carded and combed textile fibres and to separate from them the defective fibres and impurities, having in combination a series of arms, means for rapidly oscillating said arms, rulers mounted on said arms, each one of said rulers being provided with a slot through which the fibres pass, said rulers serving to shake the fibre, and a series of rollers which guide and feed the fibres through the grooves of the rulers to be thrashed and shaken, and thus obtain 120 125 130

the separation of the defective fibres and impurities.

3. A machine to soften carded or combed textile fibres and to separate the defective fibres and impurities, having in combination 5 a series of shaking rulers mounted on arms, means for rapidly oscillating said arms in order to beat the fibres repeatedly, each one of said rulers being provided with a groove through which pass the fibres to be shaken 10 by the motion of the ruler, guiding and feeding rollers which cause the fibres to pass through the grooves of the thrashing rulers, and means to invert the position of the fibres 15 after having passed through a certain number of shaking rulers in such a way that the upper face of the lap or sliver remains at the lower side and thus the impurities accumulated on this side are more easily dislodged.
- 20 4. A machine to soften carded or combed textile fibres and to separate the defective fibres and impurities, which comprises a stand which supports rolls of fibres previously carded or combed, a guide which carries 25 these fibres to the shaking units, a series of shaking units, each of which is formed by rulers mounted at the end of rapidly oscillating arms and provided with slots through which are made to pass the fibres in the shape 30 of a lap, said fibres being shaken by the rulers, combined with couples of guide rollers which determine the advance of the lap of fibres and oblige it to pass through the shaking rulers, means to invert the position of the 35 lap of fibres in such a way that the face which was above remains below, another series of shaking units and a "Gill intersecting" or other auxiliary apparatus which collects the fibres already cleaned, submits them to a 40 combing and stretching, finally rolling them into bobbins, in order to submit them later to the customary spinning processes.

In testimony whereof I have signed my name to this specification.
